UNITED STATES PATENT OFFICE

1,966,722

GOVERNOR

Addison C. Hoof, Hinsdale, Ill.

Original application September 17, 1932, Serial No. 633,695. Divided and this application June 30, 1933, Serial No. 678,394

7 Claims. (CL. 137—152)

This invention relates to improvements in governors more particularly for gas engines, where a throttle valve is inserted in the neck of the intake manifold; and the closing movements thereof, under the forces created by the cylinder displacement at different loads for a desired speed are balanced by a spring resistance.

This application is a division of my co-pending application Serial Number 633,695, filed September 17, 1932, and an improvement upon the disclosure of application, Serial Number 443,265, filed April 11, 1930, now Patent Number 1,910,899.

Objects of this invention are to provide key controlled means for adjusting the governor, and also securing the cover of the governor housing in position. More specific objects are to provide a simple construction of the housing, cover and lock; and to provide a construction in which a common form of cylinder lock may be used, the cylinder type of lock being considered a more secure form of locking means than padlocks, bolt locks, and the like.

Further objects of the invention are to provide a governor having a key controlled adjustment, and also a closure which is locked by the same key to prevent tampering.

Other objects and advantages will become apparent in the following description of an illustrative embodiment of the invention, with reference to the accompanying drawing, in which:

Fig. 1 is a side elevation, partly in section, of the governor incorporated in a block 10 which is inserted between the bolting flanges of the engine intake manifold and the carburetor, as will be understood.

Fig. 2 is a plan section, taken substantially on the line 2—2 of Fig. 3, with parts shown in full.

Fig. 3 is a section on line 3—3 of Fig. 1.

Fig. 4 is a partial section on the line 4—4 of Fig. 3.

Fig. 5 is a detail section taken on line 5—5 of Fig. 1.

Fig. 6 is a cross section of the lock cylinder.

On one side of the block 10 is formed a housing 11, having a chamber 12 which is covered by means of a removable plate 13. An intake duct portion 14 extends vertically through the block, and in the block is journaled a horizontally disposed shaft 15 which extends through the wall on one side of the duct and into the chamber 12. In the duct a plate valve 16 is rigidly secured to the shaft; and on the outer

end of the shaft, within the housing, is pinned an arm 17—having a roller 18 rotatably mounted on its outer end. In the wide open position of the valve, the arm 17 abuts against a stop lug 18a formed on the adjacent wall of the housing.

In the base of the housing 11, below and at the side of the shaft opposite the arm 17, is formed a boss 19 in which is rotatably mounted a block 20 which has a lug 21 extending into the boss. The block 20 has a transverse slot 22 in which is clamped, by means of screw 24, a multiple graduated leaf spring 25 which extends below the shaft substantially parallel with the arm in the open position of the valve, the longest leaf being in cooperable relation with roller 18.

A screw 26 is rotatably mounted in a lug 27, formed on the lower wall of the housing, and threaded on the screw is nut 28 which is engaged in a notch 29 formed in the lower end of the block 20. Thus the spring 25 may be swung towards or away from the arm 17 by rotating the screw 26 to effect tension adjustments.

In the lower corner of the housing is provided a boss 30 which has a bore 31, in alignment with the screw 26, for receiving a lock cylinder 32, having transversely disposed locking tumblers 33. On the inner end of the cylinder is an eccentrically disposed lug 34 which enters a cross slot 35 milled in the head 36 of the screw 26, so that the rotative position of the screw is controlled by the lock cylinder.

The enlarged end 37 of the lock cylinder 32 abuts against a shoulder 38, formed in the bore 31, and oppositely disposed longitudinal slots 39 are formed in the walls of the bore for locking engagement of the tumblers 33.

The cover plate 13 is locked in position by the insertion of the cylinder 32. On the inner side of the upper edge of the plate 13 are provided two curved lugs 40 which hook into suitable slots 41 provided in the upper wall of the housing 11; and on the lower corner of the cover is a lug 42 which enters an enlarged recess 43 in the housing which is intercepted by the bore 31. The lug 42 is provided with an aperture 44 which registers with the cylinder bore 31 when the cover is in closed position, and receives the lock cylinder.

The cylinder is prevented from withdrawal by means of a radial lug 45 formed on the inner end thereof. The cylinder is inserted with the tumblers retracted and the lug 45 is passed through a notch 46 formed in one side of the

aperture 44, which registers 90° from the tumbler slots 39; and, as the cylinder is rotated to locking position the lug 45 rotates in the recess 43 and engages behind the cover lug 42.

5 The cover 13 is provided with a lug 47 for holding the block 20 in position.

In operation, the flow of the gases through the intake duct 14 tends to rotate the valve 16 towards closing position until the valve reaches

10 a position at which the torque on the shaft and opposing resistance of the spring are equal.

The resistance of the spring is built up and the stiffness of the spring increases at an ever increasing rate as the flexure is increased, and 15 this building up of resistance is further accentuated as the roller 18 rides up on the spring and moves closer to the support block 20. Thus by proportioning the various parts, and regulating the effective lengths of the leaves, the resistance can be regulated to closely approximate 20 the torque on the shaft at each position of the valve for the desired engine speed.

By changing the position of the block 20, 25 rotatively, by inserting a key 50 in the lock cylinder 32 and thus turning the screw 26, the governed speed can be changed as desired, and the resistance is increased more rapidly at higher tensions in accordance with the greater increases in the torque at closed valve positions 30 for higher speeds on account of the greater degree of flexure of the spring, so that good regulation can be obtained at different speeds.

Having thus described my invention, I claim:

1. In a gas engine governor having a housing, 35 governing means therefor, a governor adjusting screw rotatably mounted in said housing, the screw having a transversely slotted end, and a key operated lock cylinder mounted in said housing, said cylinder having an eccentric lug 40 on its inner end which enters the slot so that the screw may be rotated to adjust the governor by inserting a key in the cylinder and thus turning the lock from the exterior of the housing.

45 2. In a gas engine governor, a housing having a recess and a grooved bore intercepting the recess, governing means in said housing, a governor adjusting screw rotatably mounted in the housing in alignment with said bore, a cover 50 for the housing having a lug which enters the recess, the lug having an aperture which coincides with the bore, and a key operated lock cylinder having pins for locking engagement in the grooves capable of being inserted into the 55 bore from the exterior of the housing, the cylinder being in engagement with the screw and extending through the lug so that the cover is locked by inserting the cylinder and whereby the governor may be adjusted by turning the 60 cylinder.

3. A housing for a valve governor comprising a body member having a rectangular chamber therein, a control mechanism in said chamber,

adjusting means therefor including a screw member mounted along one wall of said chamber, a cover plate closing one side of said chamber, a pair of curved lugs thereon adapted to enter complementary openings in a wall of said body member, a lug extending at right angles from said cover plate, a bore therethrough, and a lock cylinder operatively connected to said screw member and arranged in said body member by being passed through the bore in the lug extending from said cover plate whereby said cover plate is secured to said body member.

4. In apparatus of the type described, a housing having a rectangular chamber, valve governing means therein, a governor adjusting screw mounted in said housing, a cover plate closing one side of said chamber, a pair of curved lugs thereon adapted to enter complementary openings in a wall of said body member, a lug extending at right angles from said cover plate, a bore therethrough, and a lock cylinder operatively connected to said screw member and arranged in said body member by being passed through the bore in the lugs extending from said cover plate whereby said cover plate is secured to said body member.

5. In gas engine governor construction, a housing for a governor, said housing having a recess therein and a bore intercepting the recess, a flat cover plate for one side of said housing, 105 a lug thereon capable of entering said recess, a lock cylinder mounted in said bore and extending through the lug on said cover plate, said lug having a bore therethrough coinciding through which said cylinder extends.

6. In gas engine governor construction, a housing, a valve governing means mounted therein, a flat cover plate for said housing, a spring associated with said governor, a screw for adjusting the tension of said spring mounted 115 in said housing, a non-rotatable block associated with said screw, a cylinder lock, key-operated pins extending therefrom, said pins operatively associated with said screw, said cover plate being locked in position on the housing by the 120 insertion of said lock cylinder into the housing, and key means for unlocking said cylinder to permit either the manipulation of said screw or the removal of said cover plate.

7. A housing for a valve governor comprising 125 a body member having a rectangular chamber therein, a control member in said chamber, adjusting means therefor including a screw member mounted along one wall of said chamber, a cover plate closing one side of said chamber, 130 a lug extending at right angles from said cover plate, a bore therethrough, and a lock cylinder operatively connected to said screw member and arranged in said body member by being passed through the bore in the lug extending from said cover plate whereby said cover plate is secured to said body member.

ADDISON C. HOOF.
